UNITED STATES PATENT OFFICE.

JOHN F. HEMENWAY, OF NEW YORK, N. Y.

DESIGN FOR A PRESSURE-SCREW FOR CLOTHES-WRINGERS.

51,204.

Specification for Design.

Patented Aug. 28, 1917.

Application filed June 16, 1917. Serial No. 175,216. Term of patent 14 years.

To all whom it may concern:

Be it known that I, JOHN F. HEMENWAY, a citizen of the United States, residing at New York city, in the county of New York and State of New York, have invented a new, original, and ornamental Design for Pressure-Screws for Clothes-Wringers, of which the following is a specification, reference being had to the accompanying drawing, forming part thereof.

Figure 1 is a perspective view of a pressure screw showing my design, and Fig. 2 is an inverted plan view.

I claim:

The ornamental design for a pressure screw for clothes wringers, as shown.

JOHN F. HEMENWAY.

Witnesses:

G. R. PATCHEN,
HERANT M. KIRETCHJIAN.
